DESIGN FOR A LUGGAGE CARRIER FOR BICYCLES

Horace M. Huffman, Jr., Dayton, Ohio, assignor to
The Huffman Manufacturing Company, Dayton,
Ohio, a corporation of Ohio

Application July 5, 1940, Serial No. 93,437

Term of patent 3½ years

To all whom it may concern:

Be it known that I, Horace M. Huffman, Jr., a citizen of the United States of America, residing at Dayton, in the county of Montgomery and State of Ohio, have invented a new, original, and ornamental Design for a Luggage Carrier for Bicycles, of which the following is a specification, reference being had to the accompanying drawing, forming a part thereof, and in which

Fig. 1 is a perspective view of a luggage carrier for bicycles showing my new design;

Fig. 2 is a plan view thereof; and

Fig. 3 is a side elevational view thereof.

The design comprises a rounded marginal portion and a central flattened member located in spaced relation with respect to the marginal portion throughout the greater part of its length, both the central and marginal portions having a downward curvature at the outer end thereof.

I claim:

The ornamental design for a luggage carrier for bicycles, substantially as shown and described.
